CLAIM

The ornamental design for a fry rack, as shown and described.

DESCRIPTION

FIG. 1 is a perspective view of a fry rack showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view in a use condition.

The dotted lines in FIG. 8 represent environment that forms no part of the claimed design.

1 Claim, 4 Drawing Sheets
